UNITED STATES PATENT OFFICE.

WILLIAM M. STEINLE, OF TOLEDO, OHIO, ASSIGNOR OF ONE-HALF TO JOHN BOWMAN, OF ALLEGHENY CITY, PENNSYLVANIA.

GRAIN-BINDER.

SPECIFICATION forming part of Letters Patent No. 375,659, dated December 27, 1887.

Application filed April 18, 1887. Serial No. 235,176. (No model.)

To all whom it may concern:

Be it known that I, WILLIAM M. STEINLE, a citizen of the United States, and a resident of Toledo, in the county of Lucas and State of Ohio, have invented certain new and useful Improvements in Grain-Binders; and I do hereby declare that the following is a full, clear, and exact description of the invention, which will enable others skilled in the art to which it applies to make and use the same, reference being had to the accompanying drawings, which form a part of this specification, in which—

Figure 1 is a perspective view of my improved hand grain-binder. Fig. 2 is a side view of the same. Fig. 3 is a front view. Fig. 4 is a top view of the binding mechanism. Fig. 5 is a sectional view on line $x-x$, Fig. 4. Fig. 6 is a similar view on line $y-y$, Fig. 4. Figs. 7, 8, 9, 10, and 11 are perspective views of the knotter and its surrounding and co-operative parts, showing the several steps in forming the knot; and Figs. 12 and 13 are respectively a perspective and a sectional detail view of the clamp for securing the ends of the cord above the knotter.

Similar numerals of reference indicate corresponding parts in all the figures.

My invention has relation to so-called "hand-binders" for binding grain from the field by hand-power, either binding the sheaves or bundles as they are left by a reaping-machine or by a reaper using a cradle; and it consists in the improved construction and combination of parts of a device, by means of which the grain is bundled and tied with a cord carried upon the device by means of a suitable knotting mechanism operated by hand, as hereinafter more fully described and claimed.

In the accompanying drawings, the numeral 1 indicates a handle, from which two arms, 2, diverge toward the front end of the machine, the diverging forward ends of these arms being united by means of a cross-piece, 3, and a table, 4, secured between them. Two semi-circular bars, 5, are secured at their rear ends to a cross-piece, 6, about midway of the diverging arms, and these bars are secured parallel to each other to near their forward downwardly-curved ends, where they diverge, be-

ing secured to the ends of the forward cross-piece, having curved teeth or prongs 7 formed at their ends, projecting below the table and cross-piece. A handle, 8, has its inner end secured between the semicircular bars at the point where they commence to diverge, and a strip, 9, is secured with its upper end to near the end of this handle, and has its lower portion secured to the forward cross-piece, being extended below the same into a curved prong or tooth, 10. A bolt, 11, is inserted through the diverging arms 2, at the center of the arc on which semicircular bars are formed, and two arms, 12, are pivoted by sleeves 13 at their inner ends upon this bolt, and have a curved needle, 14, secured with its inner end between the outer ends of the arms, a brace, 15, serving to furthermore secure the needle to the arms.

A bifurcated arm, 16, is pivoted near its inner end upon the inner side of one of the needle supporting arms near the pivotal point of the same, and has a spring, 17, secured to the inner end and to the arm above the pivotal point, drawing the bifurcated arm toward the sleeve of the arm, and a cord, 18, is secured to the brace of the needle and passes between the bifurcated ends of the arm under the table and up around a pulley or sheave, 19, in the forward end of the same, over a sheave, 20, upon the segmental bars, and is secured to the outer portion of a lever, 21, fulcrumed with a sleeve, 22, upon the central bolt between the sleeves of the needle-arms and sliding between the segmental bars, with its outer portion having a handle, 23, at the outer end. As the bifurcated end of the lever 16 is below the point at which the needle is pivoted to the frame, the cord 18, as it passes from the needle to the lever 21, is thrown so far below the pivotal point that the draw upon the needle will swing it around more easily than if the cord passed as close to the pivotal point as it would were the arm not used, as in that case the draw upon the needle would be more nearly toward the center of the circle in which the needle moves. The needle is provided with an eye, 24, near the end, and has a groove, 25, in its back, which is provided with a number of transverse pins or staples, 26, confining the twine 27 in the said

groove, the twine being held in a suitable box or receptacle, 28, between the converging ends of the arms, and being sufficiently retarded in its passage to the needle by means of a tension-spring, 29, upon the semicircular bar, having a screw, 30, passing through one end into the said bar, the twine passing between the spring and the bar and being more or less retarded as the screw is drawn more or less into the bar.

A coiled spring, 31, is secured with its forward end to the forward end of one of the semicircular bars, and has a cord, 32, secured to its rear end, which cord is secured to one of the needle-arms, the said spring serving to draw the needle up under the semicircular bars, while the lever, by being tilted rearward, will serve to draw the needle downward and thereupon upward, bringing the eye before the forward end of the device and bringing the needle and cord to encircle a sheaf or bundle which may have been rolled up by the teeth or prongs at the forward end of the device.

The cord 18 will compress the sheaf or bundle between it and the curved teeth or prongs, so that the strain of compressing the same will not fall upon the twine, the free end of which is held above the knotting device upon the table by a clamping-lever, 33, having a beveled inner end, 34, and secured to the outer yielding end, 35, of an elastic arm, 36, pivoted to rock in a vertical plane at one end upon a small bracket, 37, upon one of the semicircular bars, bearing against the edges of the said bars, and having a spring, 38, attached to it and to the bar, drawing it upward.

The outer end of the clamping-lever projects beyond the free end of the pivoted arm, and the inner face of the inner arm of the lever 40 has a vertical groove, 39, registering with a similar groove, 40, in the face of the arm, and a bolt, 41, is secured to the inner arm of the lever near the groove and passes through the arm, sliding in the same, and has its inner end secured to 45 the free end of a flat spring, 42, upon the inner side of the pivoted arm, the said spring drawing the beveled and grooved end of the lever toward the outer face of the arm, permitting the said end of the lever, however, to yield to 50 the end of the twine being inserted between the lever and arm.

The free end of the twine is secured each time a sheaf is bound between the beveled end of the lever and the face of the arm, the 55 grooves in the meeting faces allowing the ends of the twine to drop out as they are cut off by the cutter of the tying mechanism, and gradually pushed toward the grooves by the new ends inserted.

60 The tying mechanism is secured upon the table, which is provided at its forward edge, formed by the forward cross-piece, with a curved guard, 43, and which has upon its upper side a longitudinal partition or bar, 44, 65 extending from the central pivotal bolt to the upper portion of the central tooth or prong.

A bracket, 89, is secured upon the side of this partition near the inner end of the same, and a flat bar or arm, 45, is pivoted to rock in a plane with the table upon a bolt, 46, projecting through the lower end of the bracket and through the inner end of the bar. The inner end of this bar is provided with an upwardly-projecting bearing, 47, having a square or rectangular longitudinal perforation, 48, which registers with a similar perforation or bearing, 49, in an upright block, 50, upon the outer or forward end of the bar or arm, the said end projecting beyond the forward cross-piece. The inner end of a flat bent spring, 80 90 95 100 105 110 115 120 125 130 135 140 145 150 155 160 165 170 175 180 185 190 195 200 205 210 215 220 225 230 235 240 245 250 255 260 265 270 275 280 285 of the bail. A coiled spring, 75, is secured to this arm near the curved inner end and to the rear end of the partition, serving to draw the notch into engagement with the pin when the lever is tilted rearward, bringing the pin to register with the notch.

The knotter consists of the shaft 76 and of a foot, 77, bent at a right angle to the shaft, and this foot is formed with a rounded or beveled heel, 78, and with a straight outwardly-projecting prong, 79, and with a hooked prong, 80, having its curved end pointing toward the straight prong and slightly inward. A flat slightly-curved guard lip, 81, is secured to the upper portion of the central prong or tooth, projecting with its inner end over the knotter when the latter is tilted to that side, and a cross-bar, 82, is secured between the diverging ends of the semicircular bars above the forward cross-piece, and is provided with a pair of flaring guard-fingers, 83, the inner converging ends of which form a notch, 84, registering with the space between the inner side of the curved guard and the guard-lip. A rectangularly-bent cutter-lever, 85, is pivoted at its bend near the inner side of this notch, having the sharp cutting-edge 86 of its short arm sliding upon and toward one of the fingers, and having one end of a spring, 87, secured to its longer arm and to the cross-piece, drawing the said arm inward, and the sliding rack-bar is provided with a forwardly-projecting flat bar, 88, secured with its downwardly-bent inner end upon the nutted bolt pivoting the notched arm to the bar, and having a notched or shouldered outer end, which may bear against the long arm of the cutter when the rack-bar is forced forward, bringing the cutting-edge against the finger, the shouldered or stepped portion of the end of this bar passing over the upper end of the forward bearing-block of the pivoted arm carrying the knotter.

When now the binder is to be used, the machine is drawn by the handle so as to cause the teeth or prongs to rake up the bundle, whereupon the operating-lever, which has been tilted forward, allowing the spring to draw the needle and its arms upward, is tilted rearward and down, drawing the needle under the bundle and compressing the latter between the teeth and the cord, as shown in Fig. 2, where the bundle is shown in section. The end of the twine has previously been secured in the twine-holder above the knotting mechanism, passing from the same through the notch between the guide-fingers and between the curved guard and the guard-lip, being thereupon carried around the bundle, and having the end extending from the eye of the needle resting in the notch and within the guards at the side of the end held by the holder. The parallel ends of the twine are thus held against what might be termed the "instep" of the foot of the knotter, the end of which projects outward and within the guard-lip, and when now the operating-lever is tilted forward, as shown in

dotted lines in Fig. 2, the pin in its bail having engaged the notch, the sliding bar is forced forward, causing the upper arm of the journaled sleeve, which has been resting in the forward slot of the bar, to bear against the side of the same, tilting the pivoted arm to the side, away from the partition. This will cause the portions of twine bearing against the foot of the knotter to be drawn out of the straight line, and as now the rack portion of the bar engages the pinion of the knotter the foot of the latter will in revolving twist the portions of the twine around itself, bringing the upper ends of the first loop, which is numbered 80 in Roman cipher I forward of the lower ends, the said ends being respectively numbered in Roman ciphers II and III. As the sliding bar now progresses, its rear slot will reach the upper arm of the sleeve, giving the knotter 85 its second movement in the direction of its axis, while it at the same time revolves, bringing the upper ends of the twine in between the prongs of the knotter as the foot revolves forward, so that these ends may form the second loop, 14, as the knotter is revolved forward and downward, the weight of the bundle upon the lower ends dragging the first loop off from the foot and over the second loop, thus forming the knot. The upper ends have in the meantime been cut by the cutter, so that the weight of the tied bundle may draw the second loop off from the hooked prong, which prong has held the said loop, while the first loop was drawn over the same and tightened, 100 and it will be seen that the knot thus formed cannot be loosened by the expansion of the sheaf or bundle, as drawing on the lower ends will tighten the knot, while the knot may be opened by drawing on the upper ends, which 105 will cause the knot to be untied when going through the thrashing-machine, the knot being held tied by the expansion of the bundle and consequent draw upon the lower ends.

The progress will be readily seen by reference to the five last figures of the drawings, in which every stage of the knot is plainly illustrated, the ends and loops being numbered as they are formed in Roman cipher.

The operation of the device, then, in brief, 115 is as follows: When the handle 23 is operated to draw the needle up by means of cord 18, the pin in the handle slides along bar 69, which is held against it by spring 75 until it reaches or passes the notch in the bar. As the lever 23 120 is returned to its normal position it engages bar 69 and so slides the knotter-operating rack and the knot is tied, the second strand of the band having been laid in the holder by the needle and retained therein. This movement 125 of the lever permits the needle to yield to the action of spring 31 and be returned to place, and in so returning strikes bar 69 and lifts its notch off the pin and the spring 75 draws the rack-bar back to place.

It follows that any other form of knot-tyer may be used with the frame and that the knotter

and its operating mechanism may, with a few modifications, be applied to any self-binding reaper or hand-binding mechanism upon a reaper, the two mechanisms being applicable separately to other mechanisms, although they co-operate in this device.

Having thus described my invention, I claim and desire to secure by Letters Patent of the United States—

1. In a hand grain-binder, the combination of a frame consisting of two diverging arms united at the rear ends by a handle and two semicircular bars secured parallel with each other at one end between the converging ends of the arms, and with their diverging ends to the forward ends of the arms, having teeth or prongs at the diverging ends, an operating-lever pivoted at its inner end upon a bolt in the center of the semicircular bars, a curved needle having a twine threaded in its eyed outer end, and having its inner end secured to arms pivoted with their inner ends upon the central bolt, a cord secured to the operating-lever and passing over guide-sheaves upon the semicircular bars, and at the forward end of the frame being secured to near the inner end of the needle, a spring for drawing the needle back, and a knotting mechanism for tying the twine secured above the pronged ends of the semicircular bars and operated by the operating-lever, as and for the purpose shown and set forth.

2. In a hand grain-binder, the combination of a frame consisting of two diverging arms united at the rear ends by a handle, and of two semicircular bars secured with their rear ends between the rear portions of the arms, and having their forward diverging ends secured to the diverging ends of the arms, and having curved prongs at their forward ends, and of a central prong extended upward to a brace supporting a forwardly-projecting handle, a twine-box secured to the rear ends of the arms, a tension device upon the rear end of one of the semicircular bars, a segmental needle having a twine-receiving groove in its back bridged by pins, and an eye at its outer end and secured to the outer ends of arms pivoted upon a bolt central to the semicircular bars passing through the diverging arms and braced by an inclined brace between the arms and the inner portion of the needle, a bifurcated arm pivoted near its curved end upon the side of one of the arms of the needle, and having a spring attached to its end and to the said arm, an operating-lever pivoted at its inner end upon the central bolt and sliding between the semicircular bars, having a handle at its outer end, a cord secured to the lever and passing over pulleys upon the semicircular bars and near the forward end of the frame and between the forked end of the bifurcated arm, being secured to the brace of the needle, a spring secured to the forward end of the frame and to one of the needle-arms, a twine-holder upon the forward portion of the frame, and a knot-

ting mechanism below the holder for tying the twine, as and for the purpose shown and set forth.

3. In a grain-binder, the combination of a bar pivoted at one end and having a spring forcing it to one side, and provided with blocks at its ends formed with longitudinal bearings, a knotter journaled with the end of its shaft in the outer bearing and having a pinion within the bearing, and provided with a foot formed with a rounded heel and with a straight prong and with an inwardly-hooked prong at its end, a bar sliding in the bearings and having suitable means for reciprocating it, and formed with a smooth forward portion, and with a rack portion near the middle meshing with the pinion, and having longitudinal slots in it at the forward portion of the rack portion and to the rear of the same, a sleeve journaled at the side of the sliding bar upon a bolt of the rocking bar, and having an arm at its upper end bearing against the side of the sliding bar engaging the slots of the same, and having an arm at its lower end at a right angle to the same and bearing against an abutment-plate at the side of the rocking bar near its free end, a spring secured at its rear end, and having a curved loop at its forward end passed around the sleeve and over the upper arm of the same, and guides holding the twine at right angles to the shaft of the knotter, and having a cutter at one side of the knotter, as and for the purpose shown and set forth.

4. In a grain-binder, the combination of a table having a partition or wall, and having a plate upon the said partition near the outer end extended to form a curved guard, and having a guard-lip upon the end of the partition projecting inward and toward the inner side of the curved guard, a cross-piece having diverging guide-fingers, forming a notch registering with the space between the guard and the lip, a rectangularly-bent cutter having its fulcrum at the bend, and having its cutting-edge registering with one finger, and having a spring secured to its long arm, drawing it inward, a bar pivoted at its inner end upon the table, and provided with blocks having longitudinal bearings at its ends, and with a spring drawing it toward the partition, a knotter journaled with its shaft in the forward block, having a pinion within the bearing, and having a foot at its end formed with a rounded heel and with a straight prong, and with an inwardly-hooked prong, a bar having means for reciprocating it, and having a smooth forward portion sliding in the forward bearing and a rack portion meshing with the pinion and a smooth rear portion, and formed with a longitudinal slot in the forward portion of the rack portion and to the rear of the same, a sleeve journaled at the side of the sliding bar upon a vertical bolt upon the rocking bar, and having an arm at its upper end bearing against the sliding bar

engaging the slots and an arm at the lower end at a right angle to the upper arm, and bearing against the abutment-plate upon the partition, a spring secured at the rear end to the partition, and having a loop at the forward end passed around the sleeve and secured over the upper arm, and a flat bar secured above the sliding bar upon it and parallel to it and engaging the long arm of the cutter

when pushed forward, as and for the purpose is shown and set forth.

In testimony that I claim the foregoing as my own I have hereunto affixed my signature in presence of two witnesses.

WILLIAM M. STEINLE.
